UNITED STATES PATENT OFFICE.

ROBERT EMIL WALther, OF WERDAU, GERMANY.

DEVICE FOR OPENING PRESERVE-TINS.

1,071,974.

Specification of Letters Patent.

Patented Sept. 2, 1913.

Application filed February 16, 1912. Serial No. 678,007.

To all whom it may concern:

Be it known that I, ROBERT EMIL WALther, a subject of the German Emperor, and residing at Werdau i. Sa., Germany, 5 have invented certain new and useful Improvements in Devices for Opening Preserve-Tins, of which the following is a specification, reference being had therein to the accompanying drawing.

10 This invention relates to a device for opening preserve tins by means of an adjustable cutter or the like the inventive idea of which is that the movement of the cutter and the supporting roll is brought about by 15 a rotatably movable shaft provided with a ribbed wheel on its free end together with the guide rolls bearing on the outer edge of the tin in such a manner that the device moves around the tin in conformity with the 20 rotation of the shaft, while the tin itself remains stationary.

Two forms of this device are shown in the drawing.

Figure 1 is a side elevation of the device, 25 Figs. 1^a and 1^b are enlarged views of details to be described hereinafter. Fig. 2 is a plan view thereof. Fig. 3 is a plan view of a modification as viewed from below. Fig. 4 is an end elevation partly in section.

30 In the body *a*, which may be given any desired form, a shaft bearing a ribbed roll *c* and provided with a handle is mounted.

Rolls or pins *e* which may be set in accordance with the form of the tin by means 35 of the slit guides *f* and the thumb nut *g*, are mounted on the lateral projections *d*. By means of the guides *f* or the rolls *e* the device is given the necessary rigidity and the cutter *h* is prevented from slipping off the 40 surface to be cut, thus securing a clean cut without any bur.

Fixed underneath the cast-iron body is a thumb nut *i* with a threaded bolt, which latter being connected to an obliquely projecting arm serves to press the supporting roll under the backwardly bent edge of the tin in order that the cutter *h* may be pressed in the edge of the tin so that the device is caused to move around the edge of the tin

by the ribbed wheel *c* when the handle fixed 50 on the shaft is turned. Fixed on the opposite side of the body *a* is a thumb nut *l* which serves to set the cutter for cutting the tin in known manner, the projecting stop *m*, which may be replaced by a handle fixed 55 under the body *a*, is for the purpose of giving the device the correct position upon the tin to be opened, so that the projecting supporting roller *k* correctly engages under the 60 backwardly turned edge of the tin.

In Figs. 3 and 4 the body *a* is shown in the form of a pair of tongs. When the edge of the preserve tin is gripped with these tongs between the guide rolls *e* and the supporting roll *k*, and the ribbed wheel *c* 65 pressed against the edge of the tin by pressing the shanks of the tongs together, the cutter *h* pierces the lid of the tin. The shanks of the tongs are then held together by the spring-device *d'* or the like, so that 70 when the shaft is turned by the handle and the preserve tin held stationary, the tool is moved around the tin and the cutter *h* cleanly cuts out the lid of the tin without 75 bur.

Having thus described my invention, what I claim as new, and desire to secure by Letters Patent, is:—

A device for opening cans comprising a body, a shaft on said body, a ribbed roller 80 and a handle on said shaft, arms laterally adjustable on said body having slots near their inner ends, a thumb screw to hold said arms in position, adjustable projections pivoted to the lower ends of said body and to 85 said arms, grooved wheels on said projections to engage the upper edge of the can, a cutter operatively supported on the lower part of said body and means to hold the device in operative position.

In testimony whereof I have signed my name to this specification in the presence of two subscribing witnesses.

ROBERT EMIL WALther. [L. S.]
